[57] CLAIM

The ornamental design for a shoulder belt cover or similar article, as shown and described.

DESCRIPTION

FIG. 1 is a top plan view of a shoulder belt cover or similar article showing my new design;

FIG. 2 is a side elevational view;

FIG. 3 is a side elevational view of a shoulder belt cover or similar article showing a second embodiment of my new design;

FIG. 4 is a top plan view of FIG. 3; and

FIG. 5 is a top plan view of FIG. 3 shown partially folded;

FIG. 6 is a top plan view shown in a position of use, the broken line showing of a seat belt is for illustrative purposes only and forms no part of the claimed design; and

FIG. 7 is a top plan view shown in the position of use, the broken line showing of an automobile, driver and seatbelt being for illustrative purposes only and forming no part of the claimed design.

FIG. 1
